[57] CLAIM

The ornamental design for a funnel with long ribbed spout, as shown and described.

DESCRIPTION

FIG. 1 is a front elevational view of a funnel with long ribbed spout showing our new design, the rear elevational view being the same but reversed;

FIG. 2 is a top plan view thereof;

FIG. 3 is a right-side elevational view thereof;

FIG. 4 is a left-side elevational view thereof; and,

FIG. 5 is a bottom plan view thereof.
